UNITED STATES PATENT OFFICE.

FRANK M. ASHLEY, OF NEW YORK, N. Y.

DESIGN FOR AN INKSTAND.

No. 39,166.

Specification for Design.

Patented March 8, 1908.

Application filed November 30, 1906. Serial No. 345,846. Term of patent 14 years.

To all whom it may concern:

Be it known that I, FRANK M. ASHLEY, a citizen of the United States, residing at West Sixth street, corner Dewey avenue, in the city of New York, borough of Brooklyn, Coney Island, State of New York, have invented a new, original, and ornamental Design for Inkstands, of which the following is a specification.

Referring to the accompanying drawing, the figure is a perspective view of an inkstand disclosing my new, original and ornamental design.

I claim:

The ornamental design for an inkstand, as shown.

FRANK M. ASHLEY.
